WILLIAM E. SIEVERS AND OTTO HAMMER, OF WHITTIER, CALIFORNIA, ASSIGNEES TO
SECURITY INVESTMENT COMPANY OF WHITTIER, OF WHITTIER, CALIFORNIA, A
CORPORATION OF CALIFORNIA

WELL REAMER

Application filed November 20, 1930. Serial No. 496,917.

This invention relates to improvements in well reamers and may be considered an improvement over the construction disclosed in an application for a well reamer filed by John A. Vertson, October 17, 1929, Serial No. 400,316.

An object of the present invention is to provide an improved well reamer having roller like cutters which are mounted on the body 10 of the reamer in such a manner as to be rotatable about axes which are both laterally inclined and downwardly and inwardly inclined. In this manner the reamer when considered as an entirety is downwardly 15 tapered so as to gradually enlarge the hole and distribute the wear evenly throughout the lengths of the respective cutters.

Another object of the invention is to provide a well reamer having laterally inclined 20 roller like cutters, which cutters may also be downwardly and inwardly inclined, with the cutters so mounted that the reamer may assume a contracted position or an expanded position enabling the reamer to be lowered 25 through a well casing and then to expand and ream the well hole below the casing.

A further object of the invention is to provide a well reamer comprising a body and cutter holders mounted on the body which carry 30 the cutters, these cutter holders providing for expansion of the reamer and also enabling a cutter to be easily and quickly removed and replaced.

With the foregoing and other objects in 35 view, which will be made manifest in the following detailed description, and specifically pointed out in the appended claims, reference is had to the accompanying drawings for an illustrative embodiment of the invention, 40 wherein:

Fig. 1 is a view in side elevation of the improved reamer.

Fig. 2 is a partial view in section taken substantially upon the line 2—2 upon Figure 45 1 in the direction indicated.

Fig. 3 is a horizontal section taken upon the line 3—3 upon Figure 1, illustrating the reamer in expanded position.

Fig. 4 is a top plan view of the improved reamer.

Fig. 5 is a view similar to Figure 3, illustrating the reamer in contracted position.

Fig. 6 is a horizontal section taken substantially upon the line 6—6 upon Figure 1.

Referring to the accompanying drawings, 55 wherein similar reference characters designate similar parts throughout, the improved reamer comprises a body generally designated at 10, shown as having at its upper end a pin 11 and at its lower end a box 12, making provision for incorporating the reamer in a string of drill pipe. The body 10 between the pin and box is downwardly tapering in form as shown upon Figure 1. At intervals on its peripheral surface there 60 are formed recesses 13, the rear ends of which are semi-circular in form with the forward side being arranged on approximately a tangent thereto. These recesses are laterally inclined as indicated by the construction shown in Figure 1 and as the body 10 tapers the recesses are also downwardly and inwardly inclined, as will be apparent from an inspection of Figure 2. At the top and bottom of each recess there is a boss, the upper 65 boss being designated by the reference character 14 and the lower boss by the reference character 15. Cutter holders 16 fit between the bosses, having semi-circular backs which fit snugly in the semi-circular rear ends of the 70 recesses 13. These cutter holders have top and bottom outwardly extending arms 17 and 18 and are pinned in place by pins 19 extending through the bosses 14 and 15 respectively. These pins may be locked in in any suitable 75 manner, such as by threads, set screws, locking pins, or the like. The cutter holders 16 can pivot on the pins 19 and assume an expanded position as shown in Figure 3 or contracted positions as shown in Figure 5 where-

in the cutter holders are lying against the tangential sides of the recesses. Cutters 20 fit between the outstanding arms 17 and 18 of the cutter holders and are rotatable upon 5 pins 21 which extend through the upper arms 17 and partially through the lower arms 18. These pins are locked in place as by a locking pin 23 and a small hole 24 is left in the lower arm 18 permitting pin 21 to be punched 10 out of the cutter holder when it is desired to replace a cutter.

The cutters 20 have scarifying edges or teeth formed thereon which are shown as being helical in form. It will be readily appreciated, however, that the particular nature of the scarifying teeth may vary. The cutters 20 present longitudinally curved exteriors so that they are somewhat barrel shaped in form. In the Vertson application, above referred to, the cutters are preferably true ellipsoidal frustums. In the present case, however, the cutters are slightly modified from this shape due to the fact that the axis of rotation of each cutter is downwardly and inwardly inclined as well as being laterally inclined. The lower end of the cutter is of minimum diameter whereas the central portion is of greater diameter and the upper portion has a diameter between the 20 diameters of the central portions and lower portions. The cutters are preferably given this shape so that each cutter will bear against the well hole throughout substantially its entire length. Consequently during the remaining operations the reamer first encounters the walls of a small hole which it is desired to ream. The lower portions of the cutters enlarge this hole slightly and 40 the central portions of the cutters continue the enlargement, with the upper ends of the cutters completing the enlargement and reaming the hole to a new size. In this manner the wear on the scarifying edges will be distributed throughout the entire length 45 of each cutter and as the cutters may rotate during the scarifying action the wear will be distributed completely around each cutter. By thus distributing the wear completely 50 around each cutter and over its entire length, the life of any particular cutter will be materially prolonged.

The improved reamer is highly advantageous over prior well reamers having cutters rotatable about vertical axes or axes which are radially inclined in that such constructions merely pack the walls of the well, frequently having a knurling action. In the improved construction the scarifying edges effectively scrape the walls of the well with a smooth discing action so that when casing 60 is subsequently lowered there is little or no danger of its becoming hung in the well. The 65 flutes 25 which are arranged between the re-

cesses 13 facilitate upward flow of circulation fluid past the reamer.

By comparing Figure 5 with Figure 3 it will be appreciated that the reamer can be 70 lowered into the well with the cutters in contracted positions as shown in Figure 5. After reaching the desired location in the well rotation of the reamer toward the right causes the cutters to encounter heavy mud present 75 in the well with the result that the cutter holders 16 will swing outwardly into the position shown in Figure 3. Their pivotal movement is limited in this position by the sides 80 of the cutter holders engaging the rear edges of the recesses. While the resistance offered by the mud ordinarily is sufficient to swing the cutter holders into expanded positions, such movements may be assisted by springs 85 recessed in the body and urging the cutter holders into expanded positions. These springs may be arranged at the top and bottom of the cutter holders or may be omitted entirely as above indicated.

From the above described construction it 90 will be appreciated that an improved well reamer has been developed which advantageously reams the well by a scarifying action. The improved reamer by virtue of the taper 95 in its construction gradually enlarges the hole and distributes the wear over the entire cutter.

Various changes may be made in the details of construction without departing from the spirit or scope of the invention as defined by 100 the appended claims.

We claim:

1. A well reamer comprising a body, cutter 105 holders mounted on the body for pivotal movements between limits about axes which are downwardly and inwardly inclined as well as laterally inclined, and cutters rotatably mounted in the cutter holders.

2. A well reamer comprising a body, cutter 110 holders mounted on the body for pivotal movements between limits about axes which are downwardly and inwardly inclined as well as laterally inclined, and cutters rotatably mounted in the cutter holders, said cutters each presenting a longitudinally curved exterior so as to be capable of bearing against a well wall throughout substantially their 115 entire lengths.

3. A well reamer having cutters rotatable about axes which are downwardly and inwardly as well as laterally inclined, each cutter presenting a longitudinally curved exterior so as to be capable of bearing against a well wall throughout its complete length.

4. A reamer comprising a body, cutter 125 holders pivotally mounted upon the body for a limited pivotal movement about laterally inclined axes, cutters carried by the cutter holders and adapted to be swung through arcs in advance of their respective axes, there 130

being means for limiting the outward swinging movements of the cutter holders.

5. A reamer comprising a body, cutter holders pivotally mounted upon the body for a limited pivotal movement about laterally inclined axes, cutters carried by the cutter holders and adapted to be swung through arcs in advance of their respective axes, there being means for limiting the outward swinging movements of the cutter holders to positions wherein the cutters are held in their outermost positions.

10 6. A reamer comprising a body, said body having a cutter holder pivotally mounted upon the body for a limited pivotal movement about a laterally inclined axis, and a cutter carried by the cutter holder adapted to be swung thereby through an arc in advance of said inclined axis.

20 7. A reamer comprising a body, cutter holders pivotally mounted upon the body for limited pivotal movements about laterally inclined axes, cutters rotatably mounted upon the cutter holders, said cutters having a general shape which is longitudinally curved so that they may engage the walls of the well throughout substantially their complete lengths, said cutters being adapted to be swung through arcs in advance of the axes of their respective cutter holders, there being provision made for limiting the outward swinging movements of the cutter holders.

25 8. A reamer comprising a body, cutter holders pivotally mounted upon the body for limited pivotal movements about laterally inclined axes, cutters rotatably mounted upon the cutter holders, said cutters having a general shape which is longitudinally curved so that they may engage the walls of the well throughout substantially their complete lengths, said cutters being adapted to be swung through arcs in advance of the axes of their respective cutter holders, there being provision made for limiting the outward swinging movements of the cutter holders to positions wherein the cutters are held in their outermost positions.

30 9. A reamer comprising a body, cutter holders pivotally mounted upon the body for limited rotation about axes which are downwardly and inwardly as well as laterally inclined, and cutters carried by the cutter holders adapted to be swung thereby through arcs in advance of their respective axes.

35 10. A reamer comprising a body, cutter holders pivotally mounted upon the body for limited rotation about axes which are downwardly and inwardly as well as laterally inclined, and cutters carried by the cutter holders adapted to be swung thereby through arcs in advance of their respective axes, there being provision made for limiting the outward swinging movements of the cutter holders.

40 11. A reamer comprising a body, cutter

holders pivotally mounted upon the body for limited rotation about axes which are downwardly and inwardly as well as laterally inclined, and cutters carried by the cutter holders adapted to be swung thereby through arcs in advance of their respective axes, there being provision made for limiting the outward swinging movements of the cutter holders, said cutters having a general shape which is longitudinally curved in such a manner that when the cutters are in their outermost position they will engage the walls of a well throughout substantially their complete lengths.

45 12. A well reamer comprising a body, cutter holders pivotally mounted upon the body for movements about laterally inclined axes between limits, and roller cutters rotatably mounted upon the cutter holders for rotation in cutting position about laterally inclined axes, said cutters being mounted upon the cutter holders in positions in advance of the axes of the cutter holders.

50 13. A well reamer comprising a body, cutter holders pivotally mounted upon the body for movements about laterally inclined axes between limits, and roller cutters rotatably mounted upon the cutter holders for rotation in cutting position about laterally inclined axes, said cutters presenting longitudinally curved exteriors so designed that the cutters during cutting may bear against the walls of the well throughout substantially their entire lengths.

55 14. A well reamer comprising a body, cutter holders pivotally mounted upon the body for movements about laterally inclined axes between limits, and roller cutters rotatably mounted upon the cutter holders for rotation in cutting position about laterally inclined axes, said cutters being mounted upon the cutter holders in positions in advance of the axes of the cutter holders, said cutters presenting longitudinally curved exteriors so designed that the cutters during cutting may bear against the walls of the well throughout substantially their entire lengths.

60 15. A well reamer comprising a body, cutter holders pivotally mounted upon the body for movements about laterally as well as downwardly and inwardly inclined axes between limits, and roller cutters rotatably mounted upon the cutter holders for rotation in cutting position about laterally inclined axes.

65 16. A well reamer comprising a body, cutter holders pivotally mounted upon the body for movements about laterally as well as downwardly and inwardly inclined axes between limits, and roller cutters rotatably mounted upon the cutter holders for rotation in cutting position about laterally inclined axes, said cutters being mounted upon the cutter holders in positions in advance of the axes of their respective cutter holders.

17. A well reamer comprising a body, cutter holders pivotally mounted upon the body for movements about laterally as well as downwardly and inwardly inclined axes between limits, and roller cutters rotatably mounted upon the cutter holders for rotation in cutting position about laterally inclined axes, said cutters being mounted upon the cutter holders in positions in advance of the axes of their respective cutter holders, said cutters presenting longitudinally curved exteriors so designed that the cutters during cutting may bear against the walls of the well throughout substantially their entire lengths.
18. A well reamer comprising a body, cutter holders pivotally mounted upon the body for movements about downwardly and inwardly as well as laterally inclined axes between limits, and roller cutters rotatably mounted upon the cutter holders for rotation in cutting position about downwardly and inwardly as well as laterally inclined axes.
19. A well reamer comprising a body, cutter holders pivotally mounted upon the body, means limiting outward movements of the cutter holders to cutting positions, and roller cutters rotatably mounted upon the cutter holders for rotation in cutting position about downwardly and inwardly as well as laterally inclined axes.
20. A well reamer comprising a body, cutter holders pivotally mounted upon the body, means limiting outward movements of the cutter holders to cutting positions, and roller cutters rotatably mounted upon the cutter holders for rotation in cutting position about laterally inclined axes, said cutters being longitudinally curved and so designed that during cutting operations they will bear against the walls of the well throughout substantially their complete lengths.
21. A well reamer comprising a body, cutter holders pivotally mounted upon the body, means limiting outward movements of the cutter holders to cutting positions, and roller cutters rotatably mounted upon the cutter holders for rotation in cutting position about downwardly and inwardly as well as laterally inclined axes, said cutters being longitudinally curved and so designed that during cutting they will bear against the walls of the well throughout substantially their complete lengths.
22. A well reamer comprising a body rotatable about its longitudinal central axis, cutter carriers pivotally mounted upon the body for movements about laterally inclined axes, and roller cutters rotatably mounted upon the cutter carriers for rotation about axes which are parallel to the laterally inclined axes of their respective cutter carriers.
23. A well reamer comprising a body rotatable about its longitudinal central axis, cutter carriers pivotally mounted upon the body for movements about laterally inclined axes,

and roller cutters rotatably mounted upon the cutter carriers for rotation about axes which are parallel to the laterally inclined axes of their respective cutter carriers, said cutters being longitudinally curved and so designed that during cutting they will bear against the walls of a well throughout substantially their complete lengths.

24. A reamer comprising a body rotatable about its longitudinal central axis, cutter carriers pivotally mounted upon the body for movements about downwardly and inwardly as well as laterally inclined axes, and roller cutters rotatably mounted upon the cutter carriers for rotation about axes which are parallel to the downwardly and inwardly as well as laterally inclined axes of their respective cutter carriers.

25. A reamer comprising a body rotatable about its longitudinal central axis, cutter carriers pivotally mounted upon the body for movements about downwardly and inwardly as well as laterally inclined axes, and roller cutters rotatably mounted upon the cutter carriers for rotation about axes which are parallel to the downwardly and inwardly as well as laterally inclined axes of their respective cutter carriers.

26. A well reamer comprising a body rotatable about its longitudinal central axis, cutter carriers pivotally mounted upon said body for movements between limits, and cutters rotatably mounted upon the cutter carriers for rotation about axes parallel to the axes of pivotal movement of the cutter carriers.

27. In a reamer, a vertical elongate body rotatable about a central axis, and an elongate roller cutter mounted on the body and extending in its cutting position diagonally upwardly and outwardly and circumferentially with respect to the body axis so that the upper end of the cutter lies outward of and circumferentially displaced from the lower end.

28. In a reamer, a vertically elongate body rotatable about a central axis, and an elongate roller cutter mounted on the body and extending in its cutting position diagonally upwardly and outwardly with respect to the body axis and also diagonally with respect to a plane radial of the body axis.

29. In a reamer, a body rotatable about its vertical central axis, an elongate roller cutter mounted upon the body and extending in its cutting position diagonally upwardly and outwardly with respect to the body axis and also diagonally with respect to a plane radial of the body axis, said cutter having circumferentially extending teeth thereon presenting outer edges which are inclined to the horizontal designed to scarify the walls of a well.

30. In a reamer, a body rotatable about its vertical central axis, an elongate roller cutter mounted upon the body and extending in its cutting position diagonally upwardly and

outwardly with respect to the body axis and also diagonally with respect to a plane radial of the body axis, said cutter having circumferentially extending teeth thereon presenting 5 outer edges which are inclined to the horizontal designed to scarify the walls of a well, the outer edges of all of the teeth being arranged on a curve longitudinally of the cutter so that each cutter will have each tooth engage 10 the walls of the well and conically ream it.

In testimony whereof we have signed our names to this specification.

WILLIAM E. SIEVERS.
OTTO HAMMER.
